N° 3057

H. M. Sherwood

Design for School Desk and Seat Frames.
PATENTED

MAY 26 1868

Fig. 1.

Witnesses,

G. G. Chapin *Henry M. Sherwood*
A. Maynard

United States Patent Office.

HENRY M. SHERWOOD, OF CHICAGO, ILLINOIS.

Design No. 3,057, dated May 26, 1868.

DESIGN FOR THE FRAME OF A SCHOOL-DESK AND SEAT.

The Schedule referred to in these Letters Patent and making part of the same.

TO ALL WHOM THIS MAY CONCERN:

Be it known that I, HENRY M. SHERWOOD, of Chicago, in the county of Cook, and State of Illinois, have invented or produced a new Design for School-Desk and Seat-Frames; and I do hereby declare that the following is a full, clear, and exact description of the same, reference being had to the accompanying photographic sketch, and the letters marked thereon, making a part of this description, in which—

Figure 1 is a perspective representation of my invention.

This invention relates to a cast-iron seat and desk-frame, and it is ornamented with beads, scroll-work, and basso-relievo, in such a manner as to give a desirable appearance.

To enable others to fully comprehend, make, and use my invention, I have marked the principal parts with distinct letters, and will now give a detailed description.

Fig. 1 represents the end or frame, which is made of a single piece of cast iron, and with curved legs, A B, terminating in a single standard, L, to which the back of the seat is attached.

A little above the intersection of the legs is an arm, C, under which is a curved brace, D, having a bead on its outer front edge, for relieving the flat surface, and the standard L has a projecting arm, K, under which is a curved brace, H, reaching from the standard to the end of the arm, and connecting with a short brace, I.

That part of the frame enclosed between the arm K, brace H, and standard L has an S-shaped scroll, S, in the concave parts of which are smaller scrolls and figures, carved in basso-relievo, so as to give the design a neat and tasty appearance.

The legs A B are ornamented on their front faces with ribs or beads, as is also the brace G, which, together with the other characteristics above mentioned, provide a frame for the ends of seats and desks which is very simple and ornamental, and also of such a pattern as can be easily made by persons of ordinary skill.

Having thus described my invention, what I claim, and desire to secure by Letters Patent of the United States, is—

The design for a school-desk and seat-frames, substantially as herein set forth and shown.

HENRY M. SHERWOOD.
